(57) **CLAIM**

The ornamental design for a pipe fitting, as shown and described.

DESCRIPTION

FIG. 1 is a perspective view of the pipe fitting;
FIG. 2 is a rear perspective view of the pipe fitting;
FIG. 3 is a front view of the pipe fitting;
FIG. 4 is a rear view of the pipe fitting;
FIG. 5 is a right side view of the pipe fitting;
FIG. 6 is a left side view of the pipe fitting;
FIG. 7 is a top view of the pipe fitting;
FIG. 8 is a bottom view of the pipe fitting;
FIG. 9 is a perspective view of the pipe fitting in an extended configuration;
FIG. 10 is a rear perspective view of the pipe fitting in the extended configuration;
FIG. 11 is a front view of the pipe fitting in the extended configuration;
FIG. 12 is a rear view of the pipe fitting in the extended configuration;
FIG. 13 is a right side view of the pipe fitting in the extended configuration;
FIG. 14 is a left side view of the pipe fitting in the extended configuration;
FIG. 15 is a top view of the pipe fitting in the extended configuration; and,
FIG. 16 is a bottom view of the pipe fitting in the extended configuration.
